UNITED STATES PATENT OFFICE.

REMIGIUS D'ANTONIO, OF CAPESTRANO, ITALY.

MARINE PROPULSION.

988,697.

Specification of Letters Patent.

Patented Apr. 4, 1911.

Application filed March 24, 1910. Serial No. 551,285.

To all whom it may concern:

Be it known that I, REMIGIUS D'ANTONIO, a subject of the King of Italy, residing at Capestrano, Aquila, Abruzzi, Italy, have invented certain new and useful Improvements in Marine Propulsion, of which the following is a specification.

This invention relates to marine propulsion.

10 The object of the invention is in a novel and practical manner to propel a vessel either backward or forward by the employment of alternating jets of water discharged in planes parallel with the line of the keel, 15 and by the employment of laterally discharging jets of water to effect turning of the vessel about its center as an axis. Furthermore, to utilize the apparatus either to clear the hold of water, or to supply the 20 water to the hold for the purpose of extinguishing a fire.

With the above and other objects in view, as will appear as the nature of the invention is better understood, the same consists in the 25 novel construction and combination of parts of an apparatus for steering and propelling a vessel as will be hereinafter fully described and claimed.

In the accompanying drawings forming a 30 part of this specification, and in which like characters of reference indicate corresponding parts: Figure 1 is a view in the nature of a diagram exhibiting the manner in which a vessel is steered or propelled. Fig. 35 2 is a top plan view, partly in section, of the apparatus. Fig. 3 is a vertical longitudinal section of the apparatus. Fig. 4 is an end view. Fig. 5 is an end elevation looking in the direction of the arrow x , in Fig. 2. Fig. 40 6 is a top plan view. Fig. 7 is a sectional detail view of one of the air-controlling valves. Fig. 8 is a collective detail view showing the construction of the steam-controlled valve.

45 As the apparatus shown in Fig. 2 is duplicated at each end of the vessel, both parts operating independently of each other, a description of one will serve for both. The mechanism embodies two water-receiving 50 cylinders, 1 and 2, and two steam-receiving cylinders 3 and 4, these four cylinders being securely bolted to a suitable base to retain them in alinement. The water-receiving cylinders are provided with two upwardly 55 opening valves 5 and 6, and 7 and 8 respectively and arranged within said cylinders

are piston-heads 9 and 10, connected by piston-rods 11 and 12 with the piston-heads 13 and 14 of the steam-cylinders, the rods working in appropriate stuffing-boxes 15 and 16 carried by the opposed ends of the cylinders. Arranged within each of the cylinders 3 and 4 are two rods 17 and 18, 19 and 20. Each of the rods 18 and 19 carries two collars 21 and 22, and each of the rods 17 and 20 carries a collar 23 and 24. The four rods work in suitable bearings formed in the cylinder-heads 3 and 4, and work loosely in orifices provided in the piston-heads 13 and 14. The outer end of each of the rods 17 and 20 carries a valve 25 and 26 respectively, and a coiled spring 27 is carried by the inner end of each of the rods and bears upon the outside of the inner heads of the cylinder 3 and 4, said springs serving normally to hold 75 the valves in close juxtaposition to the outer heads of the cylinders 3 and 4. These valves work in casings 27 and 28 that project from the outer heads of the cylinders 3 and 4. Connecting with the cylinders 1 and 2 is a 80 water-supply pipe 29 (Fig. 4) that leads to a suitable source of supply, and includes a branch pipe 30 controlled by a valve 31 to pump water from the hold of the vessel. Tapped into each of the cylinders 1 and 2 is 85 a pipe 32, Fig. 3 which communicates with a valve-casing 33, the latter being in communication with an air-dome 34, and coupled with the pipe 32 is a branch pipe 35 controlled by a valve 36, the object of the branch 90 pipe being to supply water to any part of a vessel in case of fire. With the casing 33 are connected six pipes 37, 38, 39, 40, 41, and 42, Fig. 2. Of these the pipes 39 and 40 discharge in the line of the keel, while the remaining pipes discharge at right angles thereto, and are utilized for steering purposes, whereas the former pipes are utilized 95 for propulsion.

As stated, the various objects designed 100 are secured by employing alternating pulsations or jets of water, and one of the novel features resides in the employment of pneumatic pressure for controlling the operation of the valves that open or close the 105 pipes 37-42, a detail of this arrangement being shown in Fig. 3, in which but two of the valves 43 and 44, and one valve 45 for controlling passage of water through the pipe 40 are shown. Each of the valves 110 43 and 44 has connected with it a stem 46 and 47 which projects through one end of

the valve-casing, coiled springs 48 arranged on the stems within the casing serving normally to hold the valves seated. The valve 45 is provided with a similar stem 49 and spring 50 for holding it seated. It is to be understood, of course, that the six valves coöperating with the pipes 37-42 operate independently. Connected with each of the valve-casings of the pipes is one end of a pipe 51, 52, 53, 54, 55, and 56 respectively, the other end of each of which connects with a pipe 57 and 58 respectively which connect with the valves 61, 62, 63, 64, 65 and 66 carried by the pipes 51, 52, 53, 54, 55 and 56 respectively the four pipes 58, 59, 57 and 60 being tapped into the valve-casings 27 and 28.

Arranged adjacent to the valve-casings 27 and 28 is a pipe 67 that leads to a suitable reservoir containing air under pressure, and leading from the pipe 67 are two branch-pipes 68 and 69 that are tapped into the casings, 27 and 28 respectively. Each of the valves 25 and 26 is provided with a port 70 and 71 respectively which are of a size to establish communication between the outlet 57 and the pipes 58 and 68, and the outlet 58' and the pipes 57 and 69.

Each of the cylinders 3 and 4 is provided with two ports 72, 73 and 74, 75, respectively, that coöperate with two slide valves 76 and 77 working in suitable chests 78 combined with the cylinders, clearly shown in Fig. 2. Combined with the exterior of the outer heads of the cylinders 3 and 4 and with the chests are shafts 79 and 80 respectively, one being disposed above and the other below the horizontal axes of the cylinder. Journaled upon the rods 79 and 80 are arms 81, 82, 83 and 84, and with these are connected the rods 18 and 19 and the valve-rod 85 and 86.

Connecting with the air-supply pipe 67 are two branch pipes 87 and 94, the former of which is tapped into the larger end of the air-dome 34. Mounted upon the pipe 67 is a valve-casing 89, shown in detail in Fig. 7, and in which is mounted a valve 90 having a transverse port 91 arranged, under certain conditions, to register with the pipe 67, a coiled spring 92 encircling the stem 93 of the valve serving to hold the same normally seated.

The pipe 67 has connected with it a branch pipe 94, and the pipe 87 has connected with it a branch 95, and these two branches support a pressure-gage 96, having two hands, one of which indicates the pressure in the pipe 67, and the other the pressure in the pipe 87.

When it is desired to operate the mechanism of propulsion, steam is allowed to pass through the pipe to the valves 76 and 77 which control the admission of steam to the cylinders 3 and 4. In the position in which

the cylinders are shown in Fig. 2, steam will be in the act of passing by means of the valve 77 to the piston-head 14 which being forced forward, in consequence, will produce a two-fold action; namely, striking the collar 22 on the rod 19 which is attached to a revolving shaft 80, the latter connecting with the valve 76 of the opposite cylinder 3, it will cause the valve 76 to assume such place as will set its openings in juxtaposition with the openings of the steam-pipe 97, thus allowing steam to pass to the piston-head in cylinder 3 to force the former backward; and secondly, the piston-head 14, striking against the collar 24, on the rod 20 which is attached to the valve 26, will bring the openings of said valve 26 into such position as to establish communication between the compressed-air pipe 69 and the pipe 57 which connects with the cocks that regulate the passage of the air to the jet-valves 42, 41, 40, 39, 37 and 38. From this brief description of the action produced by the admission of steam to cylinder 4, it will be evident that the time during which the valve 26 will remain in position to allow the passage of compressed-air from the pipe 67 to the cocks, as well as the interval between each successive opening and closing of said valve 26, will be determined by the greater or less velocity in the motion of the piston-head, the velocity of the latter depending in turn upon the greater or less amount of steam admitted to the cylinders.

Movements similar to those in cylinder 4 will be produced by the admission of steam into cylinder 3; and the piston-head 13 being forced backward, will release pressure from the collar 23 on the rod 17; which latter being brought to its normal position by the spring 27 will cause the air-valve 25 to assume the position as indicated in regard to air-valve 26, thus shutting off communication between the air-pipe 58 and the pipe 68 and establishing communication between the pipe 58 and the atmosphere at 57. Furthermore, the piston-head 13 is forced back and strikes the collar 21 attached to the rod 18, this latter being connected by a shaft 79 with the steam-valve 77, will cause the valve 77 to move in the same direction as that of the piston-head 13, thus allowing the steam to pass through to the cylinder 4. The action of the cylinders will be alternated, this being due as well to the alternate opening and closing of the valves 76 and 77, as to the difference in structure of the valves themselves.

When the steam pumps are in motion in the manner described the piston-rod 12 attached to the piston-head 10 in the water cylinder 2, will cause the piston-head 10 to move forward thus by the force of suction drawing the water into the cylinder 2 through the water-valve 97, indicated by dotted lines in Fig. 2. As the piston-head 130

returns in the opposite direction, it forces the water thus drawn in, through the valve 7 and through this to the pipes 98, (indicated by dotted lines in Fig. 3), and 29 whence it passes to the jet-valves 42, 41 etc. While this action is taking place, water is likewise being drawn in on the other side of the piston-head 10 through the valve 99, Fig. 3, the water on the return stroke of the piston-head being forced through the valve 8 thence through the pipes 98 and 29 to the jet-valves. A similar operation takes place in cylinder 1, the water being admitted through the valve 100 and passing outward through the valves 5 and 6 and the pipes 98 and 29.

The water that is forced to the several jet-valves by the action of the pumps will remain under pressure until the jet-valves are opened by the force of the compressed air from the air-pipes 54, 55, 56, 53, 52 and 51. On inspection of the drawings, it will be noted that, while the jet-valves are arranged in pairs as shown in Figs. 2 and 3, the pipes that convey the compressed air to the jet-valves are so disposed as to correspond alternately now to one and then to the other cylinder of the pump. Since, as has been stated, the action of the pumps is alternated, such arrangement of the air-pipes will result in an alternated discharge of water from the several pairs of jet-valves, with such brief interval, however, between each alternate discharge as to make said discharge practically continuous, and thus do away with the dead-zone that would result were there but a single continuous discharge of water. The passage of the compressed air to the pipes 56, 55, 54, 53, 52 and 51, and thence to the jet-valves is regulated by the cocks 66, 65, 64, 61, 62 and 63, and the valve 89, shown in detail in Fig. 7. The purpose of the valve 89 is to prevent the passage of air from the reservoir until the pressure of the water on the air in the air-dome 34 is sufficiently great to cause the opening 91 of said valve 89 to be set in juxtaposition with the air-pipe 67. It will be understood therefore that under such conditions the jet-valves can only be opened to allow the discharge of water when this latter is under a given pressure, determined both by the greater or less velocity in the action of the steam-pumps and by the greater or less resistance of the spring 92 in the valve 89, said spring being of such construction as to allow of its being set to any given tension. It will also be understood that when the mechanism is in operation, other things being equal, the intervals between the successive opening and closing of valve 89 will be so brief as practically to keep said valve continually open. As the compressed air passes through the valve 89 to the pipe 69, its further passage to the pipe 57 will be determined by the

position of the air-valve 26, as hereinbefore stated. The opening, then, of cocks 66, 65, 64, 61, 62 and 63 will permit the compressed air to pass to the several pipes 54, 55, 56, 53, 52 and 51, and thence to the jet-valves. Lastly the opening and closing of the cocks 66, 65, 64, 61, 62 and 63, will be regulated by any suitable electric device operated from a key-board or levers in the engine-room or elsewhere, the electrical mechanism forming no part of the present invention.

I claim:

1. Means for propelling and steering vessels comprising duplicate devices at each end of the vessel, each consisting of a pair of juxtaposed jet pipes arranged longitudinally adjacent in the line of the keel to discharge at the end of the vessel and pairs of juxtaposed transverse jet pipes arranged to discharge on opposite sides of the vessel, a pair of water cylinders provided at their opposite ends with valved inlets, pistons working in said cylinders, a water supply pipe communicating with said valved inlets, automatically closing valves controlling communication between the supply pipe and respective jet pipes, steam cylinders arranged in line with the water cylinders, pistons operating therein, rods connecting the pistons of the aligned water and steam cylinders to move in unison, a source of compressed air supply, sets of valved conducting pipes leading therefrom to said controlling valves, whereby the latter may be opened by air pressure, air feed valves respectively controlling communication between the sets of air pipes and the source of air supply, steam feed valves controlling the supply of steam to the ends of the steam cylinders, means controlled by the pistons in the steam cylinders for alternately opening and closing the air feed valves, and means controlled by said pistons for alternately opening and closing the steam feed valves.

2. Means for propelling and steering vessels comprising duplicate devices at each end of the vessel, each consisting of a pair of juxtaposed jet pipes arranged longitudinally adjacent in the line of the keel to discharge at the end of the vessel and pairs of juxtaposed transverse jet pipes arranged to discharge on opposite sides of the vessel, a pair of water cylinders provided at their opposite ends with valved inlets, pistons working in said cylinders, a water supply pipe communicating with said valved inlets, automatically closing valves controlling communication between the supply pipe and respective jet pipes, steam cylinders arranged in line with the water cylinders, pistons operating therein, rods connecting the pistons of the aligned water and steam cylinders to move in unison, a source of compressed air supply, sets of valved conducting pipes leading therefrom to said controlling valves,

whereby the latter may be opened by air pressure, air feed valves respectively controlling communication between the sets of air feed pipes and the source of air supply, 5 steam feed valves controlling the supply of steam to the ends of the steam cylinders, spring-retracted rods for actuating the air feed valves, said rods being operated to open the valves by the pistons in one direction of movement of the latter, and means including sliding rods operative in reverse directions by the reverse movements of the pistons to open and close the steam valves.

3. Means for propelling and steering vessels comprising duplicate devices at each end of the vessel, each consisting of a pair of juxtaposed jet pipes arranged longitudinally adjacent in the line of the keel to discharge at the end of the vessel and pairs of juxtaposed transverse jet pipes arranged to discharge on opposite sides of the vessel, a pair of water cylinders provided at their opposite ends with valved inlets, pistons working in said cylinders, a water supply pipe communicating with said valved inlets, automatically closing valves controlling communication between the supply pipe and respective jet pipes, steam cylinders arranged in line with the water cylinders, pistons operating therein, rods connecting the pistons of the aligned water and steam cylinders to move in unison, a source of compressed air supply, sets of valved conducting pipes leading therefrom to said controlling valves, whereby the latter may be opened by air pressure, air feed valves respectively controlling communication between the sets of air feed pipes and

the source of air supply, steam feed valves controlling the supply of steam to the ends of the steam cylinders, spring-retracted rods 40 slidably mounted upon the steam cylinders and extending through the steam pistons, contacts on said rods adapted to be engaged by the steam pistons to alternately operate the rods to open the air feed valves, means 45 for operating the steam-feed valves including rods slidably mounted upon the steam cylinders and through the steam pistons, and contacts on said rods adapted to be engaged by the steam pistons to alternately open and 50 close the steam valves.

4. An apparatus for propelling and steering a vessel comprising pairs of juxtaposed pipes arranged at each end thereof and disposed in the line of the keel and at right 55 angles thereto, water-receiving cylinders in communication with the pipes, pistons arranged within the cylinders, steam cylinders in line with the water cylinders, pistons in said steam cylinders connected to 60 move in unison with the aligned pistons in the water cylinders, means controlled by said steam pistons for supplying steam for actuating said pistons, valves carried by the pipes, means for supplying air to the valve 65 casings, and means governed by the steam pistons for controlling the passage of air to the casing.

In testimony whereof I affix my signature in presence of two witnesses.
